UNITED STATES PATENT OFFICE.

WILLIAM F. DAVIS, OF MILWAUKEE, WISCONSIN.

EXPLOSIVE-ENGINE.

SPECIFICATION forming part of Letters Patent No. 694,948, dated March 11, 1902.

Application filed January 2, 1900. Serial No. 99. (No model.)

To all whom it may concern:

Be it known that I, WILLIAM F. DAVIS, a resident of the city and county of Milwaukee, State of Wisconsin, have invented certain new and useful Improvements in Explosive-Engines, of which the following is a full, clear, and exact description.

In the accompanying drawings the invention is shown as embodied in an explosive-engine more particularly designed for the propulsion of motor-vehicles; but it will be readily understood that features of the invention are applicable to explosive-engines of the stationary type.

15 The invention consists of the features of improvement hereinafter described, illustrated in the accompanying drawings, and particularly pointed out in the claims at the end of this specification.

20 Figure 1 is a plan view of a motor-vehicle provided with an explosive-engine embodying my invention. Fig. 2 is a view in side elevation, the wheels at one side of the vehicle being removed. Fig. 3 is a view, upon an enlarged scale, showing the rear end of the engine and parts connected therewith. Fig. 4 is a view in vertical cross-section through the frame of the motor-vehicle looking toward the front and with the cylinders of the engine

25 removed. Fig. 5 is a view in central vertical longitudinal section upon line 5 5 of Fig. 3, the view being upon an enlarged scale and showing only the rear part of the mechanism supported by the vehicle. Fig. 6 is a view in vertical longitudinal section through the cam-shaft and connected parts shown more particularly in Fig. 4. Fig. 7 is a view in section on line 7 7 of Fig. 6. Fig. 8 is a detail view of the pump-cylinder, the piston-rod, and certain of the parts connected therewith. Fig.

30 Fig. 9 is a detail view, in side elevation, of the hub of one of the rock-arms whereby the movement of the pump-piston is effected. Fig. 10 is a detail view, in vertical section, of the hand-lever and gear-wheel for controlling the throttle-valve. Fig. 11 is a detail front view of the transverse frame which supports the cylinders.

35 A and A' designate the rear traction-wheels of the motor-vehicle, and A² and A³ denote the front wheels. The rear traction-wheels

are connected with the frame of the vehicle by means of the axle B, and the front wheels are connected with the frame by means of the axle B'. The frame of the vehicle is shown as 55 comprising side bars C and C', suitably held together by transverse connections. The traction-wheels A and A' are driven from the counter-shaft D by sprocket-chains d, carried by suitable sprocket-wheels connected with the 60 traction-wheels A A', and the counter-shaft D has revolution imparted thereto from a main drive-shaft E in any suitable manner, that is sustained by the side bars C C' of the vehicle-frame. The mechanism for transmitting revolution from the drive-shaft E to the traction-wheels forms no part of my invention, however, and need not be more particularly described.

Between the side bars C and C' of the main 70 frame extends a transverse frame or casting F, that is suitably bolted, as at f, to the side bars of the vehicle-frame. This transverse casting F comprises a transverse web f', having inwardly-extending annular flanges f², 75 vertical flanges f³, and horizontal flanges f⁴. The flanges f³ and f⁴ serve to receive bolts or rivets, that unite the transverse frame F to the side bars C and C' of the vehicle-frame. The annular flanges f² serve to receive the 80 twin cylinders G and G' of the explosive-engine. The inner ends g of the cylinders G G' extend through the openings formed in the transverse frame F, and the cylinders are securely bolted to this frame. The head of 85 each of the cylinders G G' (see Fig. 3) is provided with suitable openings to receive the admission and exhaust valve casings g' and g² and with similar openings receive the igniter-casing g³. As the construction of the 90 admission and exhaust valves and of the igniter forms no part of my present invention, these features need not be particularly described.

Across the front of the cylinders G G' extends a shaft 2, that is secured in suitable bearing-brackets 3 and 4, that are bolted to and project outwardly from the faces of the cylinder-heads. Upon this transverse shaft 2 are journaled the hubs of the several valve-operating levers H, H', H², and H³. On this transverse shaft 2 is also journaled the hub

9, provided with rocking arms, whereby the pump mechanism will be operated in manner to be presently described.

The air-delivery pipe 10 is connected by a 5 branched coupling 11 with suitable channels leading into the heads of the cylinders G and G'. This construction of coupling 11 and the manner of connecting it with the cylinder-heads is fully described in an application ex- 10 ecuted by me and filed in the United States Patent Office of even date herewith and need not be more particularly described.

Into the air-delivery pipe 10 leads the throttle-valve casing 12, (see Fig. 5,) opposite the 15 delivery-port of which is located the needle-valve 13, that serves to control the passage of fuel through the discharge-port of the valve-casing 12. With the throttle-valve-casing 12 connects an oil-supply pipe 14, where- 20 by oil is supplied from a tank 15^a, suitably suspended beneath the cylinders of the engine or in other convenient location. The oil-supply pipe 14 is fitted with the usual check-valves 15 and 16 and is connected by a 25 T-shaped coupling 17 and pipe with the cylinder 18 of the oil-supply pump. From the outer end of the pump-cylinder 18 the return pipe 19 leads back to the oil-tank 15^a, so that any oil that passes beyond the pump-piston 30 may be returned to the tank. The throttle- 35 valve 13 works through a screw-threaded opening in the valve-casing 12, and a suitable threaded cap, that is attached to the outer end of the casing 12, serves to secure the packing around the valve 13. To the outer end of the throttle-valve 13 is fixed a hand- 40 lever J, whereby the valve 13 may be turned, and between the hand-lever J and a collar k is a gear-wheel K, that is loosely mounted 45 upon the stem of the throttle-valve 13. The gear-wheel K meshes with a rack-bar K', that is held in engagement with the gear-wheel by means of a guide plate or bracket k', that is bolted, as at k², to the top of the throttle- 50 valve casing, the outer end of the bracket k' being formed, as shown in Fig. 5, to securely retain the rack-bar K' in mesh with the gear-wheel K. Through a threaded hole in one 55 end of the hand-lever or handle J of the throttle-valve passes a set-screw j, by means of which the hand-lever J can be locked at any point with respect to the gear-wheel K. The gear-wheel when locked to the handle or hand-lever of the throttle-valve serves to operate the throttle-valve, and by thus adjustably connecting the gear-wheel to the throttle-valve the movement of the throttle-valve by the gear-wheel can be very accurately controlled.

60 By reference more particularly to Figs. 1, 3, and 5 of the drawings it will be seen that the valve-levers H, H', H², and H³ are shifted by the rods h, h', h², and h³, that extend longitudinally of the cylinders G G', the ends 65 of these rods resting upon a transverse bar 20, that is bolted to the side bars C and C' of the vehicle-frame, the rods h h', &c., be-

ing held in place by suitable guides 21, that are mounted upon the bar 20. (See Fig. 3.) The valve-levers H H', &c., will be operated by mechanism to be presently described; but it will be understood that these valve-levers have their upper ends moved outward from the cylinder-heads by the valve-rods h h', &c., the valve-levers being moved in opposite direction by the coil-springs h⁵, that are interposed between the valve-levers and the cylinder-heads of the engine. The lower end of the admission-valve levers H' and H² are provided with angular extensions h⁸, (shown 80 in Fig. 3 of the drawings,) and in the path of these extensions h⁸ project the lateral lugs 25 of the rock-arms 26, that depend from the hub 9, carried on the transverse shaft 2. The lower ends of the rock-arms 26 are pivotally connected, as at 27, (see Figs. 3 and 8,) with a yoke 28, having a hub 29, which fits over the outer end of a collar 33 on the rod 30 of the pump-piston 31. (See Fig. 5.) The collar 33 is held against slipping from the 90 end of the rod 30 by means of a collar 32, that is fastened to the end of the rod, and the collar 33 is formed with a cup-shaped end, against which bear the ends of two coil-springs 34 and 35. The opposite end of the 95 coil-spring 34 bears against the cap of the pump-cylinder 18, while the corresponding end of the coil-spring 35 bears against a collar 37, that is fixed to the piston-rod 30 of the pump. By reference to Fig. 5 it will be 100 seen that the cylinder 18 of the pump is conveniently fastened, as at 38, to the transverse frame or casting F.

From the foregoing description it will be seen that as the admission-valve levers H' and H² are operated the rock-arms 26 will force inward the yoke 28 and the sleeve or collar 33 connected therewith. The inward movement of the collar 33, through the medium of the spring 35, will shift the pump-piston 31, at 110 the same time compressing the spring 34, and the piston will be moved in opposite direction by the spring 34. The throttle-valve 13 will at certain times be approximately or entirely closed, (this being effected by mechanism to 115 be presently described,) and when this occurs it will manifestly be undesirable to force oil from the pump-cylinder to the throttle-valve casing. Inasmuch, however, as the cushion-spring 35 is interposed between the reciprocating collar 33 and the piston-rod 30, it becomes possible for the collar 33 to continue 120 its operation under the influence of the admission-valve levers without effecting the movement of the pump-piston 31, since when 125 the discharge of oil through the throttle-valve casing is cut off the movement of the pump-piston to supply further oil cannot be effected.

A further advantage incident to the above-described construction is that inasmuch as 130 the pump-piston is driven from the operating-levers of the admission-valve the extent of movement of the pump-piston and consequent amount of fuel-supply to the cylinders will

be in keeping with the extent to which the admission-valves are opened by their operating-levers. In other words, as long as the admission-valve is open pressure will be exerted upon the pump-piston to inject fuel throughout the period of admission; but as soon as the valve-gear operates to close the admission-valve then the pressure upon the pump-piston is immediately relieved and the fuel is no longer injected into the inlet-pipe.

By reference more particularly to Figs. 1, 2, and 3 of the drawings it will be seen that the rack-bar K', that serves to operate the gear-wheel K, that is adjustably connected with the throttle-valve 13, has its outer end connected with a bell-crank lever 40, that is pivoted upon an arm or bracket 41, that projects from the journal-bearing bracket 4, extending from one of the cylinder-heads. The opposite arm of the bell-crank lever 40 is connected by a rod 42 with an operating-lever M, that is pivotally sustained at the front of the machine in manner as will hereinafter more fully appear.

The rods h , h' , h^2 , and h^3 , whereby the corresponding admission and exhaust valve levers are operated, carry at their inner ends friction-rollers 47, adapted to bear against cams that are carried by a cam-shaft P, that is journaled in suitable bearings 50, that rest upon and are bolted, as at 51, to the top of the side bars C C' of the vehicle-frame. (See Figs. 1, 4, and 6.) The cam-shaft 50 is a tubular shaft, and to this shaft are keyed the cams p , that serve to control the operation of the exhaust-valve levers H and H³, the rollers at the ends of the rods h and h^3 bearing against the periphery of these cams. Upon the cam-shaft P is also mounted a shifting cam sleeve or support P', the periphery of which is provided with cams p' , that serve to control the operation of the admission-valve levers H' and H². As shown, the cam support or sleeve P' is connected to the shaft P by means of a pin p^2 , that passes through the slots p^3 , formed in the shaft P, this pin p^2 passing also through the end of a shifter-rod P³, that is mounted in manner free to slide within the tubular shaft P. By reference more particularly to Figs. 1 and 4 of the drawings it will be seen that the cams p' are gradually tapered toward one end of the sleeve or support P'. Hence it will be seen that when the sleeve P' is in such position that the rollers at the ends of the rods h' and h^2 of the admission-valve levers are in bearing against the broadest portions of the cams p' the admission-valve will be held open for a longer period during the revolution of the shaft P than would be the case if the rollers at the ends of the rods h' and h^2 were opposite the narrower portions of the cam p' . Consequently by shifting the cam sleeve or support P' the length of the period of admission can be readily varied, and this shifting of the sleeve or support P' is effected by the mechanism next to be described.

Through the outer end of the shifting-rod P³ passes a rod 54, that passes also through slots p^4 , formed in the shaft P. The rod 54 passes through a governor-sleeve 55, that encircles the shaft P in manner free to slide thereon. Upon the ends of the rod 54 are pivoted the V-shaped arms R and R' of the governor mechanism, suitable nuts 56 engaging the screw-threaded ends of the rod 54. From the apex of each of the V-shaped governor arms or frames R and R' extends an arm r, carrying a governor weight or ball r', and at the apex of each of the arms or frames R R' is pivoted upon a pin 57 the outer end of a governor-link R². The inner end of each of the links R² is pivotally connected, as at r², to the ears or offsets 58, that project from a collar 59, that is keyed to the shaft P. (See Figs. 4, 6, and 7.) From the apex of each of the governor arms or frames R extend outwardly the parallel arms r⁵, (see Figs. 6 and 7,) formed in piece therewith, these arms r⁵ being provided with notches to receive a correspondingly - shaped rib 60 on a bearing-plate 61, against which bearing-plate abuts the end of a coil-spring 62, that is carried by a rod 63. The opposite end of the coil-spring 62 bears against a shoulder 64 on the rod 63, and the adjacent end of this rod 63 is pivotally connected, as at 65, to a sliding sleeve 66, mounted upon the shaft P. The outer end of each of the rods 63 is provided with a stop-pin 67, that holds it in engagement with the arm r⁵. The sleeve 66 is connected with the shaft P by a key 68, (see Fig. 4,) so that the sleeve shall partake of the revolution of the shaft while being free to slide lengthwise thereof. The outer end of the shaft P has fixed thereto a collar 69 to guard the sleeve 66 against displacement. Upon the shaft P is mounted a gear-wheel P⁴, that will be connected by suitable gearing with the drive-shaft of the engine, so that the cam-shaft P shall move in unison with the drive-shaft. The sleeve 66 is formed with a peripheral groove, within which sets a shifter-ring 70, the trunnion-pins 71 of which are connected to the yoke-shaped end of a regulating-lever S. This lever S has its lower portion pivotally connected to a rod S', the inner end of which is pivoted to a bracket 72, projecting from the transverse frame or casting F. (See Fig. 4.) The rod S' is formed with a long slot s', through which passes a pivot-bolt s², that passes also through the lower portion of the lever S. Upon this bolt is a winged nut S³, whereby the lever S will have its lower portion set at any point along the slot s'. (See Fig. 4.) To the lever S is pivotally connected, as at s⁴, the outer end of a rod 75, the inner end of this rod being connected to one arm of a bell-crank lever 76. This bell-crank lever 76 is pivoted upon an arm or bracket 77, extending outward from one of the side bars of the vehicle-frame, (see Fig. 4,) and through the inner end of the bell-crank lever 76 passes the rod 42, that leads

to the operating-lever M at the front of the vehicle-frame. The inner end of the bell-crank lever 76 will be so connected with the rod 42 that the shifting of such rod will correspondingly shift the bell-crank lever. The operating-lever M is pivotally connected to a suitable bracket or support m, and the lower end of this lever extends adjacent a segmental ratchet-plate N, (see Fig. 2,) with the teeth 10 of which engages a latch-bar n, that is pivoted to the operating-lever M. The latch-bar n is connected by the rod n' with a grip-handle n'', that is pivoted to the upper end of the operating-lever M.

15 From the foregoing description the operation of the mechanism above described will be seen to be as follows: If the vehicle is to be run at high speed, it is manifestly desirable that the parts shall be in such position as to normally deliver to the cylinders of the engine the maximum charge of gasoline or like fuel. By forcing forward the upper end of the lever M the operator will cause the shifting rod 42 to move backward, thereby causing the outer arm of the bell-crank lever 76 (see Figs. 1 and 4) to move inward. This movement of the bell-crank lever 76 will draw inward the lever S, thereby causing the upper end of this lever to move inward correspondingly the sleeve 66. As the sleeve 66 is thus moved inward the heavy coil-springs 62 will force outwardly, through the medium of the rods 63 and bearing-plates 60, the arms r⁵ of the governor frames or arms R, causing these frames or arms to rock about their pivot-points 57. As the frames or arms R are thus rocked their lower ends will move outward the sleeve 55 and with it the shifting rod P³ within the tubular shaft P. This outward movement of the rod P³ will correspondingly shift the cam sleeve or support P' and will bring the broad portions of the cams p' opposite the rollers at the inner ends of the rods h' and h² of the admission-valve levers H' and H². Consequently as the cam-shaft P is revolved the admission-valve levers will be so operated as to effect the maximum opening of the admission-valves. As the cam-shaft P revolves it imparts like revolution to the balls or weights r' of the governor, and when the speed of the shaft P becomes excessive these balls move outward, thereby causing the inner portions of the governor arms or frames R to move inwardly, and thus through the medium of the sleeve 55 and of the rod P³ to shift the cam sleeve or support P' so that the reduced portions of the cams p' are brought opposite the rollers at the inner ends of the rods h' and h² of the admission-valve levers H' and H², thereby reducing the period during which the admission-valves are held open. It will be seen, however, that when the sleeve 66 of the governor mechanism has been moved inward by the operator in manner last described the tension of the coil-spring 62 is increased, so that these springs will not so readily permit the outward move-

ment of the governor balls or weights as would occur if the sleeve 66 were nearer the outer end of the cam-shaft P. On the other hand, if the vehicle is to be run at a comparatively low speed the operator will draw backward the upper end of the operating-lever M, so as to cause the rod 42 and bell-crank lever 76, through the medium of the rod 75 and lever S, to shift outwardly the sleeve 66, thereby reducing the tension of the springs 62 upon the arm r⁵ and permit the governor frames or arms R to move inward, and thus through the medium of the rod P³ to shift the cam sleeve or support P' until the reduced portions of the cam p' are brought opposite the rollers at the ends of the rods h' and h² of the admission-valve levers H' and H². It is manifest that the governor balls or weights R' will automatically control the shifting of the cam sleeve or support P', so that when the speed of the engine becomes excessive the reduced portions of the cam p' will be brought opposite the inner ends of the rods h' and h², that control the admission-valve levers, and when the speed of the engine decreases the more extended portions of the cam p' will be brought opposite the ends of these rods h' and h². When the engine is to be started, (with the vehicle at rest,) the operator, having first loosened the nut S³, can shift the lever S so as to cause this lever to move the governor-sleeve 66 in order to bring the reduced portions of the cam p' opposite the ends of the rods h' and h², thereby insuring that a very small charge shall be delivered to the cylinder of the engine, and thereby reducing the amount of compression at the beginning of the operation of the engine. When, however, the engine reaches its working speed, the operator will readjust the lower end of the lever S and set the wing-nut S³, after which the governor balls or weights will automatically control the shifting of the cam sleeve or support P'. By reference more particularly to Figs. 1, 2, 3, and 5 of the drawings it will be seen that when the operator moves the operating-lever M in order to bring into play the cam p' for carrying the heavy load he will at the same time force backward the rod 42 cause the bell-crank lever 40 to be rocked so that this bell-crank lever shall move toward the left (see Fig. 3) the rack-bar K'. This movement of the rack-bar K' will cause the gear-wheel K to turn in the direction of the arrow, Fig. 3, and thus open, more or less widely, the throttle-valve 13 and permit a free discharge of the fuel into the air-pipe 10. On the other hand, when the operator moves the operating-lever M in reverse manner a corresponding reverse movement of the gear-wheel K will occur, thereby causing the throttle-valve 13 to be more or less closed. Hence it will be seen that the admission-valve levers, and as well also the throttle-valve, are under the manual control of the operator, and it will be seen also that the pump whereby fuel is supplied to the cylinders being actuated by the

admission-valve levers is operated in keeping with the duration of the period of admission determined by these levers.

Having thus described my invention, what I claim as new, and desire to secure by Letters Patent, is—

1. In an explosive-engine, the combination with the supply-passage and with the admission-valve between said passage and the engine-cylinder, of a fuel-supply pipe opening into said passage, means for periodically applying a yielding pressure to the fuel within said pipe, a controlling throttle-valve between said means and said passage, lever mechanism for opening said admission-valve through variable periods of time, connections between said lever mechanism and said means whereby pressure is only applied to the fuel during said variable admission periods and once only for every power-stroke of the engine.

2. In an explosive-engine, the combination with the supply-passage and with the admission-valve between said passage and the engine-cylinder, a pump for periodically applying pressure to the fuel within said pipe, a controlling throttle-valve between said pump and said admission-valve, lever mechanism for opening said admission-valve through variable periods of time, cushion-spring connections between said lever mechanism and said pump piston-rod through the medium of which pressure is applied to the fuel only during said variable admission periods and once only for every power-stroke of the engine.

3. In an explosive-engine, the combination with a fuel-delivery pipe and with a pump for forcing fuel through said pipe having a controlling throttle-valve and with admission-valve mechanism, of governor-controlled lever mechanism for operating said admission-valve mechanism and the pump piston-rod through variable periods of time, a cushion-spring interposed between said lever mechanism and the pump piston-rod through the medium of which spring said lever operates during the forcing stroke of said pump, and a second spring interposed between said lever mechanism and a stationary part of the structure.

4. In an explosive-engine, the combination with a fuel-delivery pipe and with the admission-valve mechanism and lever mechanism for controlling said admission-valve mechanism, of a pump and means for operating the same comprising a piston-rod, a cushion-spring encircling said rod and at one end engaging a part fixed thereto, a sliding part mounted upon said piston-rod and against which the opposite end of said cushion-spring bears, a suitable connection between said sliding part and the lever mechanism that operates the admission-valve mechanism, and a second coil-spring interposed between the cylinder of the pump and said sliding part.

5. In an explosive-engine, the combination

with the supply-pipe and with the admission-valve between said supply-pipe and the engine-cylinder, of a pump for injecting fuel in a series of jets into said pipe between the outer end thereof and said valve, a controlling throttle-valve intermediate the pump and the supply-pipe, lever mechanism for operating said valve and said pump, cushion-spring connections between said lever and said pump piston-rod; means for actuating said lever mechanism comprising a shiftable cam, automatically operating governing mechanism connected with said cam for automatically shifting the same, and means connected to said governor mechanism for manually shifting said cam through the medium of said governor mechanism.

6. In an explosive-engine, the combination with a supply-pipe and with an admission-valve between said supply-pipe and the engine-cylinder, of a pump for injecting fuel in a series of jets into said pipe between the outer end thereof and said valve, a rocking lever, separate connections between said lever and said admission-valve, and between said lever and said pump, and means for operating said lever through variable periods of time, comprising a shifting rod connected thereto, a cam-shaft, an adjustable, tapered cam on said shaft and adapted to shift said rod, automatic governor mechanism connected to said cam for automatically varying the position of said cam upon said shaft and means connected to said governor mechanism for manually shifting said cam through the medium of said governor mechanism.

7. In an explosive-engine, the combination with a cylinder having suitable admission-valve mechanism, of means for operating said valve mechanism, comprising a shaft, shiftable devices on said shaft, a shifting rod connected to said devices, weighted governor-arms connected to said rod, hand-lever mechanism, and separate cushion-spring connections between said hand-lever mechanism and each arm of said weighted arms.

8. In an explosive-engine, the combination with the cylinder having suitable admission-valve mechanism, of means for operating said admission-valve mechanism comprising a cam-shaft, a cam mounted to slide upon said shaft and to revolve therewith, a rod for shifting said cam extending lengthwise of said shaft, a sliding sleeve connected to said rod, weighted governor-arms connected to said sleeve, a second movable sleeve mounted upon said shaft, suitable springs and rods interposed between said second sleeve and said governor-arms and lever mechanism for shifting said second sleeve lengthwise of the cam-shaft, said lever mechanism comprising a lever, one end of which is attached to said second sleeve and the opposite end of which is adjustably connected to the fixed part of the structure.

9. In an explosive-engine, the combination with the cylinder having suitable admission-

- valve mechanism, of means for operating said admission - valve mechanism comprising a cam-shaft, a cam mounted to slide upon said shaft and to revolve therewith, a rod for shifting said cam extending lengthwise of said shaft, a sliding sleeve connected to said rod, weighted governor-arms connected to said sleeve, a second movable sleeve mounted upon said shaft, suitable springs and rods interposed between said second sleeve and said governor-arms, lever mechanism for shifting said second sleeve lengthwise of the cam-shaft, said lever mechanism comprising a lever, one end of which is adjustably connected to the fixed part of the structure, a bell-crank lever suitably connected to said first-mentioned lever, a connecting-rod leading from said bell-crank lever and a main operating lever connected with said rod.
10. In an explosive-engine, the combination with a cylinder having suitable valve mechanism, of an automatic governor for said valve mechanism, a fuel-supply valve, a hand-lever and connections between said lever and said automatic governor and between said lever and said fuel-supply valve, whereby the operator may simultaneously control the operation of said governor and the movement of said valve.
15. In an explosive-engine, the combination with the cylinder having suitable admission-valve mechanisms, of means for operating said valve mechanism comprising a tapered cam, means for shifting the same, a fuel-delivery pipe for supplying fuel to said cylinder, a valve for controlling the flow of fuel through said pipe, suitable means for operating said valve and a hand-lever suitably connected with said valve-operating means and with the

means that effects the shifting of the cam that controls the admission-valve mechanism.

12. In an explosive-engine, the combination with the cylinder and suitable admission-valve mechanism, of means for operating said admission - valve mechanism comprising a cam-shaft having a cam mounted to slide thereon and to revolve therewith, mechanism whereby said cam is shifted lengthwise of said shaft, a fuel-delivery pipe, a throttle-valve for controlling the flow of fuel through said pipe, mechanism for operating said throttle-valve and a hand-lever and suitable connecting mechanism whereby the operator may simultaneously shift the cam upon the cam-shaft and control the movement of the throttle-valve.

13. In an explosive-engine, the combination with the cylinder and suitable admission-valve mechanism, of means for operating said admission-valve mechanism comprising a cam-shaft having a cam mounted to slide thereon and to revolve therewith, a fuel-delivery pipe, a throttle-valve therefor, mechanism for operating said throttle-valve, a pump for forcing the fuel through said fuel-delivery pipe, mechanism for operating said pump, suitable connections between said pump-operating mechanism and the mechanism that operates the admission - valve mechanism, and a hand-lever and suitable connecting mechanism whereby the operator may simultaneously shift the cam upon the cam-shaft and control the movement of the throttle-valve.
